MICHAEL J. OWENS, OF TOLEDO, OHIO, ASSIGNOR TO THE OWENS BOTTLE MACHINE COMPANY, OF TOLEDO, OHIO, A CORPORATION OF OHIO.

MEANS FOR TRANSFERRING HOT GLASS.

1,350,464.

Specification of Letters Patent. Patented Aug. 24, 1920

Application filed April 15, 1918. Serial No. 228,583.

To all whom it may concern:

Be it known that I, MICHAEL J. OWENS, a citizen of the United States, residing at Toledo, in the county of Lucas and State of Ohio, have invented new and useful Improvements in Means for Transferring Hot Glass, of which the following is a specification.

My invention relates to means for manipulating hot glass, and particularly to an improved form of transfer device by which gobs of hot plastic glass are transferred from the gob forming apparatus to molds or receptacles. In its preferred form the transfer device comprises a plurality of troughs or conveying surfaces which may be brought successively into operative position by rotating the transfer device. These surfaces are formed of wood or other suitable material to prevent excessive cooling of the glass and providing surfaces along which the glass will slide rapidly and smoothly. Suitable means are provided for supplying moisture to the conveying surfaces to prevent overheating and to secure other advantages incident to the use of a damp conveying surface. Suitable mechanism is provided for operating the transfer device automatically to bring the conveying surfaces to position in timed relation to the operation of the gob forming apparatus.

Referring to the accompanying drawings:

Figure 1 is an elevation view of an apparatus constructed in accordance with the principles of my invention.

Fig. 2 is a view of the cam actuated means for rotating the transfer device.

Fig. 3 is a fragmentary sectional view on a larger scale of the transfer device and its actuating means.

Fig. 4 is a detail showing a spring actuated dog.

Any suitable form of mechanism may be used for forming the glass into individual charges or gobs. As herein shown, the molten glass 5 is contained in a boot or extension 6 of a continuous melting furnace (not shown) and flows through an opening 7 into a divided cup or receptacle 8. A cut-off device 9 forms a temporary bottom for said cup. A continuously rotating drive shaft 10 carries a cam 11 which operates through suitable connections to swing the cut-off device 9, carried by a sleeve 12 rotatable on a shaft 13 parallel with the shaft 10. A cam

14 on the drive shaft 10 is operable through suitable connections to actuate the sectional cup 8. As a charge of glass accumulates in the cup the knife is withdrawn, after which the cup sections are separated and the gob of glass therein permitted to drop from the cup. The knife 9 is then returned to sever the gob and the cup is closed, so that the glass again accumulates to form a succeeding gob. The drive shaft makes one complete rotation during the formation of each gob. This gob forming apparatus is fully disclosed in the co-pending application of Joseph B. Graham, Serial Number 174,697, and in itself forms no part of the present invention.

The gobs of glass drop onto a transfer device 15 by which they are transferred to molds 16. The transfer device comprises a central shaft 17 which may be journaled in bracket arms 18 and 19 on a standard 20. Fixedly mounted on the shaft 17 to rotate therewith are the troughs or chutes 21. These may either be made as separate troughs or may be formed from a single wooden block comprising a central core 22 and integral radial arms 23, providing a series of troughs arranged symmetrically around the drive shaft 17. These troughs may be made of wood or other material providing a suitable surface for conveying the glass. The wood is a non-conductor of heat and provides a smooth surface along which the glass slides rapidly and smoothly. It has the property of permitting hot plastic glass to slide in contact therewith without sticking and without marring the surface of the glass.

The multiple trough device is rotated step by step to bring the conveying surfaces successively up to operative position. The means for rotating the device comprises a ratchet-wheel 24 fixed to the shaft 17. A dog 25 for rotating the ratchet is carried on a bar 26 slidably mounted for reciprocation on the bracket arm 19. The bar 26 is reciprocated by a cam 28 on the shaft 10, which cam operates through an interponent 29 pivoted at 30 to lift the bar 26 once during each rotation of the drive shaft 10. A spring 31 connected at its ends to the bar 26 and bracket 19 respectively, returns said bar. The dog 25 is pivoted at 32 to the bar 26 and projected by a spring 33. As the bar 26 is moved upward the dog

engages a tooth on the ratchet-wheel and rotates the latter until the dog slips past the tooth. During the return of the bar the dog can yield inwardly as it moves downward past the next tooth of the ratchet-wheel. A spring actuated detent 34 seats in recesses 35 in the shaft 17 and yieldingly holds the multiple trough in position, preventing overthrow of the trough and also preventing backward rotation thereof.

Means are provided for supplying moisture to the conveying surfaces to prevent overheating and to provide a damp surface for the glass to slide along. The hot glass instantly vaporizes any moisture with which it comes in contact on the conveying surface and thus forms a thin gaseous film between the glass and said surface. The moisture may be supplied in various ways. As herein shown, a pipe 36 beneath the transfer device and extending lengthwise thereof is provided with openings through which water 37 is sprayed against the under surface of the transfer device.

25 A suitably shaped funnel or guide 38 is arranged at the lower end of the conveyor for directing the gobs of glass into the molds 16. Said molds may be carried on a rotary mold frame forming part of the glass forming machine. The drive shaft 10 is connected to rotate in synchronism with said machine so that a gob of glass is discharged into each mold 16. The parts are so timed that the divided cup and cut-off 8 and 9 30 operate to drop a charge of glass on the trough 21 while the latter is stationary. The glass quickly slides down the trough and into the mold 16. While the next charge is accumulating in the cup 8, the cam 28 operates the bar 26 to rotate the transfer device 35 through 90 degrees, bringing the next trough up to position. The detent 34 then snaps into position to hold the trough stationary until it is again advanced by the driving cam.

Although the transfer device is given a step rotation for each gob or charge of glass, it will be understood that the intervals between the step rotations may be varied. For example, it might be rotated one step after every second or third gob of glass discharged thereon.

Modifications may be resorted to without departing from the spirit and scope of my 55 invention.

What I claim is:

1. A rotatable transfer device comprising a number of conveying surfaces arranged about its axis of rotation and extending 60 lengthwise thereof, and means to rotate said device step-by-step and thereby bring said surfaces serially into operative position.

2. Transfer mechanism comprising a number of troughs or chutes, a support on which 65 said chutes are mounted, and means to ro-

tate the support step-by-step about an axis and thereby bring the chutes successively to operative position, said chute extending lengthwise of said axis.

3. Transfer mechanism comprising a number of troughs or chutes, a support for said chutes, means to rotate the support step-by-step about an axis and thereby bring the chutes successively to operative position, said chutes extending lengthwise of said axis, and means to supply moisture to the surface of the chutes.

4. Transfer apparatus comprising a plurality of troughs arranged symmetrically about a common axis of rotation, and means to rotate said apparatus about said axis and thereby bring the troughs successively to inclined position, each trough being formed to convey articles in a direction lying in a plane of said axis.

5. A rotatable transfer device comprising a number of conveying surfaces arranged about its axis of rotation and extending lengthwise thereof, a toothed wheel carried by said device, and a driving dog to actuate said wheel and thereby rotate the transfer device step-by-step.

6. A rotatable transfer device comprising a number of conveying surfaces arranged about its axis of rotation and extending lengthwise thereof, a toothed wheel carried by said device, a driving dog to actuate said wheel and thereby rotate the transfer device step-by-step, and a spring detent to hold said device in a fixed position after each step 95 rotation.

7. The combination with means for segregating molten glass into individual masses or gobs, of means to receive the gobs, and mechanism to transfer the gobs to said receiving means, said mechanism comprising a plurality of inclined chutes arranged about a common axis of rotation, and means to rotate the chutes step-by-step about said axis and thereby bring them successively to position to receive a gob and direct it to said receiving means.

8. The combination with means for segregating molten glass into individual masses or gobs, of means to receive the gobs, and mechanism to transfer the gobs to said receiving means, said mechanism comprising a plurality of chutes arranged about a common axis of rotation, means to rotate the chutes step-by-step about said axis and thereby bring them successively to operative position, and means to apply a cooling liquid to the conveying surfaces while out of operative position.

9. The combination of a chute or trough, 125 means to deliver hot glass thereto, means to rotate the trough about an axis extending lengthwise thereof to thereby bring the trough periodically into position to receive the glass, and means to apply a cooling 130

liquid to the trough while out of said receiving position.

10. The combination of a chute or trough, means to deliver hot glass thereto, means to 5 rotate the trough about an axis extending lengthwise thereof to thereby bring the trough alternately to a glass receiving position and an inverted position, and means to apply a cooling liquid to the trough while inverted.

11. The combination with means for segregating molten glass into individual masses or gobs, of means to receive the gobs, and mechanism to transfer the gobs to said receiving means, said mechanism comprising 15 an inclined support, a plurality of troughs

or chutes carried by the support and extending lengthwise thereof, means to rotate the support step-by-step whereby the troughs are successively brought to operative position, and means to spray the conveying surfaces with a cooling liquid while out of conveying position. 20

12. The combination of a trough, means to deliver hot glass thereto, and means to 25 revolve the trough about an axis extending lengthwise of the trough.

Signed at Toledo, in the county of Lucas and State of Ohio, this 5th day of April, 1918.

MICHAEL J. OWENS.
